United States Patent Office

Des. 204,799
Patented May 17, 1966

204,799

GAS CIGARETTE LIGHTER

Kyoichi Yamamoto, Tokyo, Japan, assignor to Zenza
Bronica Kogyo Kabushikikaisha, Tokyo, Japan

Filed Apr. 14, 1965, Ser. No. 84,772

Claims priority, application Japan Oct. 15, 1964

Term of patent 3½ years

(Cl. D48—27)

Fig. 1

Fig. 3

Fig. 2

Fig. 4

Fig. 5

Fig. 6

Fig. 7

FIG. 1 is a plan view,
FIG. 2 is a front view,
FIG. 3 is a left side view,
FIG. 4 is a right side view,
FIG. 5 is a bottom view,
FIG. 6 is a section view taken along the line A—A of FIG. 2; and
FIG. 7 is a perspective view.

The rear, not shown, is a mirror image of the front, shown in FIG. 2.

Each part showing diagonal shadow lines in FIGS. 2, 4, 5 and 7 appears transparent.

What I claim is:

The ornamental design for a gas cigarette lighter, substantially as shown.
